FOOD DISPENSER

Frank E. Wolcott, West Hartford, Conn.

Application August 3, 1939, Serial No. 288,200

10 Claims. (Cl. 221—76)

My invention relates to food dispensers.

It has among its objects to provide an improved closure for such dispensers of the type utilizing a support and a removable dispenser adapted to be supported thereon when not in use. A further object of my invention is to provide an improved outlet closure for such a dispenser whereby it is made possible to prevent seepage from the latter when not in use, while producing a construction which not only very effectively closes the outlet from the dispenser under varying conditions, but further is adapted to be readily cleansed in such manner as to produce a sanitary construction. A still further object of my invention is to produce such an improved closure including an improved diaphragm which cooperates in an improved manner with the outlet of the dispenser element and is carried on improved means adapted to be conveniently inserted or removed from the support while having the advantages above set forth, and further being of an inexpensive construction. These and other objects and advantages of my improvements will, however, hereinafter more fully appear.

In the accompanying drawing, I have shown for purposes of illustration, one embodiment which my invention may assume in practice.

In the drawing:

Figure 1 is a side elevation, partially in section, of a food dispenser equipped with my improvement, a portion of the dispenser supporting member being broken away to facilitate illustration;

Fig. 2 is an enlarged detail section on line 2—2 of Figure 1, the outlet of the dispenser being shown in a position wherein it is closed by the diaphragm of the closure member which is then under tension;

Fig. 3 is a like sectional view of the closure member, the outlet member of the dispenser being omitted and the closure diaphragm being free from tension;

Fig. 4 is a top plan view of the closure member;

Fig. 5 is a bottom plan view of the same, and

Fig. 6 is a perspective view of the closure member.

In this illustrative construction, I have shown a food dispenser of the general type including an open topped dispenser support 1 and an upper dispenser element 2 disposed thereon when not in use, this element having a bottom applying spout or outlet, generally indicated at 3, and a top valve or diaphragm generally indicated at 4,

adapted to be operated to discharge the contents of the dispenser 2 through this outlet; improved closure means herein being provided, generally indicated at 5, and disposed in a chamber 6 in the support 1, which are adapted to close this outlet 3, as hereinafter more fully described.

In my improved construction, the closure member 5 is seated on a flat bottom 7 of the chamber 6 and is provided with an annular supporting flange 8 of less than the internal diameter of that chamber. In a preferred construction, this flange and a vertical wall portion 9, herein cylindrical and of smaller diameter, are formed of rubber of such thickness as to provide a substantial yet resilient support for an improved inner closure diaphragm, generally indicated at 10. Herein, this diaphragm is also resilient and formed of rubber, and quite thin, though somewhat thicker than the material used in the average rubber glove. As shown, it is in the shape of a cup and suspended in depending relation within the wall portion 9 and from the upper end thereof. In a preferred construction, the diaphragm 10 is of uniform thickness and integral with the upper inner periphery of the wall 9, and round and smooth on its interior and exterior in such manner as closely to resemble one-half of a hollow rubber ball, while its bottom is substantially spaced above the bottom 7 of the support 1. Attention is further directed to the fact that this diaphragm 10 is so supported by the wall portion 9 that when the dispenser 2 is not in use and is placed upon the support 1, the outlet spout 3 of this dispenser will depress and stretch the thin diaphragm 10 in such manner as to cause the latter to conform to the undersurface of the spout 3 under tension and thereby effectively close a usual axial outlet port 3a therein. Thus, in the construction illustrated, wherein the outlet 3 is provided with an annular horizontal portion 3b surrounding this port 3a and tapered outer side walls 3c leading upward from this surface 3b, it will be apparent that when the diaphragm 10 is depressed and tensioned by the insertion of the member 3, for example in the position shown in Figure 2, an axial portion of the diaphragm will extend across the port 3a and through engagement with the portion 3b surrounding that port effectively close the latter, while the whole exterior of the portions 3b and 3c on the spout 3 will be snugly gripped by the then tensioned diaphragm.

As a result of my improved construction, it is made possible to eliminate the necessity for any upwardly extending centering means on the

closure means which are receivable in the port 3a to close the latter. It is also possible to eliminate the resultant necessity for accurate centering of the dispenser in such manner as to bring the port in the spout thereof into registry with such raised centering and closing means. Further, all necessity is also eliminated for disposing the closure in either accurate axial or in fixed relation to the support 1, as, for example, by affixing the same thereto or forming the same integral with the support. Instead, with a maximum diameter of the closure flange 8 somewhat smaller than the chamber 6, it is possible merely to drop the closure unit 5 in the chamber 6. Further, irrespective of the eccentric or concentric arrangement of the member 10 and spout, it is possible to depend upon the action of the spout 3 in depressing the diaphragm 10 to effect closing in any position wherein the spout engages the diaphragm. The latter being of such light, thin construction, and free from obstructions on its round inner face, it is possible for it to conform to and effectually close the spout 3 in any of various lateral or even angular relations of unit 5 and spout 3. Further, it will be noted that due to the provision of this diaphragm and the mounting of the same on the rubber walls 9, the latter also are adapted to yield in such manner as to relieve strain upon the diaphragm and assist in returning the same to its normal up position while also increasing the effective life of the closure. Moreover, it will be observed that should there be an accumulation of seepage in the diaphragm, the latter may be readily removed from the chamber 6 for emptying and cleaning, as by merely inverting the support 1. Attention is also directed to the fact that the structure of the closure is such as to permit all portions of the same to be readily cleaned, there being no external crevices or edges so disposed as to accumulate material, such, for example, as those existing around the base of an upwardly projecting centering portion adapted to be received in the outlet port. These and other advantages of my improvements will, however, be clearly apparent to those skilled in the art.

While I have in this application specifically described one embodiment which my invention may assume in practice, it will be understood that the same is chosen for purposes of illustration and that the invention may be modified and embodied in various other forms without departing from its spirit or the scope of the appended claims.

What I claim as new and desire to secure by Letters Patent is:

1. In a resilient dispenser closure, an upstanding base having resilient cup-shaped means peripherally supported therein for conforming to and closing a concentrically or eccentrically disposed dispenser spout therein.

2. In a dispenser closure, an upstanding base

having a cup-shaped resilient diaphragm in said hollow base and supported by its upper periphery on said base.

3. In a dispenser closure, an upstanding base having a centrally disposed cup-shaped diaphragm of thin resilient material and of substantially uniform thickness supported at its upper periphery on said base.

4. In a dispenser closure, an upstanding base having a resilient cup-shaped diaphragm in the center of said base and supported at its upper periphery on said base, said diaphragm having a smooth round inner surface.

5. In a dispenser, a hollow dispenser support, a dispenser therein having a depending spout, and a resilient closure having a cup-shaped portion adapted to be conformed to and to close said spout, and a portion supporting the said cup-shaped portion by the top thereof; the said closure being removably seated in said support.

6. In a dispenser, a hollow dispenser support, a dispenser therein having a depending spout, and a resilient closure in the shape of a section of a hollow ball supported by the top thereof and, spaced above the bottom of said support and having its inner surface adapted to conform to and to close said spout.

7. In a dispenser, a hollow dispenser support, a dispenser therein having a depending spout, and a resilient closure in the shape of a section of a hollow ball spaced above the bottom of said support and having its inner surface conformable to and closing said spout, and means removably supported in said support for resiliently supporting said section at the upper periphery thereof.

8. In a dispenser closure, an upstanding base having resilient walls, and a resilient cup-shaped portion supported at its upper periphery on said base, said portion comprising a thin rubber diaphragm supported on said walls at the upper periphery thereof and stretchable to conform to the shape of a member resting therein.

9. In a dispenser closure, an upstanding base having an open center surrounded by an annular wall and a resilient diaphragm in said base and supported at its upper periphery by the said wall; said diaphragm comprising a thin rubber cup-shaped portion in the top of and depending within said base, and a flange on the base of said wall.

10. In a dispenser closure, an upstanding base comprising a resilient annular wall having a thin rubber diaphragm depending within said base and supported at the upper periphery thereof by said wall; said diaphragm being stretchable to conform to the shape of a member resting therein and the said wall being adapted to yield to the pressure from said diaphragm before the diaphragm has reached its elastic limit.
